UNITED STATES PATENT OFFICE.

WILLIAM H. ARNOLD, OF NEW YORK, N. Y.

DREDGER-BUCKET.

SPECIFICATION forming part of Letters Patent No. 652,738, dated July 3, 1900.

Application filed April 10, 1899. Renewed April 24, 1900. Serial No. 14,189. (No model.)

To all whom it may concern:

Be it known that I, WILLIAM H. ARNOLD, a citizen of the United States, and a resident of New York, (Brooklyn,) in the county of 5 Kings and State of New York, have invented certain new and useful Improvements in Dredger-Buckets, of which the following is a specification.

This invention relates to buckets for dredgers, and particularly to clam-shell buckets.

The main object of the invention is to construct a bucket for dredgers which will readily dig hard material, which will maintain its position while filling, and which may be 15 opened and closed by fluid-pressure.

With this object in view the invention consists in the construction, combination, and arrangement of parts hereinafter fully described, and set forth in the claims.

20 In the accompanying drawings, which form a part of this specification, Figure 1 represents the improved bucket open and in side elevation. Fig. 2 represents it closed and in front elevation. Fig. 3 is a side elevation of the frame. Fig. 4 is a vertical medial section of the frame, taken on line 4-4, Fig. 3. Fig. 5 represents the closed bucket in a partial plan view, the frame being sectioned on the line 5-5 of Fig. 2. Figs. 6 and 7 represent, respectively, a vertical and horizontal section of the fluid-pressure cylinder. Fig. 8 represents the compensating device for the fluid-pressure tubes.

25 The bucket has a frame 10, in the upper end of which is a slot. In this slot is pivoted an equalizing-bar 11, to the ends of which are attached the chains or cables by which the bucket is suspended. The sides of the slot protect the bar throughout its extent and also 30 the connections thereto of the suspension chains or cables. By means of this equalizing-bar the vertical descent of the bucket is insured.

To the frame 10 are hinged the shells of the 45 bucket or the scoops 12 and 13. These are shown as hinged on separate pintles 14 and 15 and are preferably so hinged since either shell may then be removed without affecting the other. They may, however, obviously be 50 hinged both on one pintle. The frame 10 extends below the shells and is terminated by a blade 16 or other suitably-formed device

which will serve as a means for anchoring the bucket or for holding it while filling in a fixed position in the material to be removed. The 55 blade 16 is preferably made of steel and riveted to the frame, so that it may be replaced by a new one when worn out or broken. The 60 scoops or shells close against the frame or the sides of said blade.

The fluid-pressure device for operating the shells is fixed in the frame 10 and preferably well down therein, so as to limit the length of the bucket as much as possible. Said device consists of a cylinder, as 17, and its piston 18, the cylinder being provided with flanges by which it is riveted or bolted to flanges 19, formed upon the frame. The cylinder 17 is shown as located between the shells, and its lower end is protected by the 70 conical enlargement 20, formed in the middle of the anchoring-blade 16. Through the middle of the frame suitable ways or guides are formed, upon which a cross-head 21 may reciprocate. This cross-head is attached to the 75 upper end of the piston 18. To the cross-head and to the upper rim of the shells 12 and 13 are hinged the A-shaped links or arms 22 for raising and lowering the shells to open and close the bucket. To brace the rims of 80 the shells during the manipulation thereof, suitable links, as 23, are pivoted to bosses on the frame and to the rim of the shells. The shells may also be strengthened each by a mid-rib, as 24, extending from the cutting 85 edge to the upper edge or rim. The rim is preferably flared outwardly, so as to strengthen the shell and to increase the capacity of the bucket. If desired, sockets, as 25 and 26, may be provided at the edges of the frame 90 for the usual guide-poles. The upper ones 25 are shown riveted to the frame, but may obviously be cast thereon or omitted.

Any suitable fluid may be used for operating the piston 18, air being preferable. A 95 tube, as 27, conducts the air to the lower end of the cylinder for raising the piston and opening the bucket, and a tube, as 28, conducts the air to the upper end of the cylinder for depressing the piston and closing the 100 bucket. The air for operating the bucket, as described, is preferably controlled from the deck of the dredger, as by means of any suitable cock by which pressure may be ap-

plied first through one tube and then through the other, as occasion requires. The exhaust may take place at the cock or at the cylinder 17, as desired, but preferably at the cock. A controlling-cock for the purpose stated is indicated at 29.

Suitable means must be provided for taking care of the air-tubes when the bucket is drawn up and for paying them out when the bucket descends. One way by which this may be accomplished is represented in Fig. 8, wherein 30 indicates the boom from which the bucket is suspended. To the boom is fixed a sheave, as 31, and below this sheave is located another one, as 32, to cooperate therewith. The latter one is mounted in any suitable manner upon a slide, so as to freely move to and from the pulley 31. The tubes are passed around the associated pulleys or sheaves several times and then secured in any suitable way to the boom—as, for instance, to nipples, as 33, which are fixed to the boom and from the opposite ends of which the tubes are continued to the controlling-cock 29. The sheaves just described serve as a compensating device. As the bucket descends the tubes run off sheave 31, thereby drawing up the sheave 32, and as the bucket is hoisted the sheave 32 descends along its track and draws in the tubes over sheave 31. The lower sheave may be weighted sufficiently to make it respond promptly to the action of the bucket. To take the strain off the tubes, a rope or cable, as indicated at 34, may be secured to the bucket and to the nipple-plate on the boom and follow the tubes about the sheaves. This will prevent the tubes from being unduly strained or flattened on the sheaves.

In operating the bucket the shells are thrown open, as seen in Fig. 1, thus causing the blade or anchor 16 to project well below them. As the bucket descends this blade is buried in the "bottom"—the material to be removed—and anchors the bucket. Then the air is turned onto the top of the piston and the shells forced into the bottom until they meet on the blade. The cutting of the shells toward the cut already made in the bottom by the blade causes a ready cleavage of the bucket-lead from the bottom. Then, too, the blade helps with the weight of the bucket to hold it down while the shells are forcing their way through the material to be raised. In a bucket operated thus by fluid-pressure the disturbing effects due to the lifting action of the bucket-closing ch. of the ordinary bucket are avoided and the complete filling of the bucket insured. When the filled bucket has been lifted and swung over the receiving-boat, it is quickly dumped by reversing the cock 29. As the piston ascends in opening the bucket it may be prevented from striking the head of the cylinder by interposing between the piston-rod and frame a buffer, as indicated at 35.

It will be noted by reference to Fig. 1 that the outer surface of each of the scoops is con-

centric with the axis of its hinge. This provides for the scoops entering the material to be removed without imparting to the bucket a lifting tendency. It will also be noted that while the outer surfaces of the scoops are concentric with the axes of the hinges the inner surfaces are eccentric thereto. This increases the thickness and therefore the strength of the scoops at their rim, where power is applied, and also renders the scoops capable of digging more deeply into the bottom.

Many changes in the shape and construction of the bucket and in the combination of parts and in the operating and controlling mechanism may be made aside from those herein shown and described without departing from the spirit of the invention.

The invention claimed is—

1. The combination with a dredging-bucket and the suspension chains or cables, of an equalizing-bar by which said chains or cables are connected to the bucket, and projections for the frame of the bucket for protecting said bar and the chain connections therewith.

2. A dredging-bucket having a frame provided with means projecting therefrom into the material to be removed for holding the bucket in a fixed position in said material while filling, and shells or scoops each hinged to said frame and means for moving them toward and from each other.

3. A dredging-bucket having a frame to which the shells or scoops are hinged and against which they close.

4. A dredging-bucket having a frame to which the shells or scoops are hinged and which terminates in a blade or anchor.

5. The combination with a dredging-bucket, having a central frame provided with an anchoring-blade, of fluid-pressure mechanism for closing the bucket.

6. The combination with a dredging-bucket provided with means for anchoring it while filling, of a fluid-pressure cylinder and piston located within the bucket and connected to the outer edges of the shells for closing and opening them.

7. In a dredging-bucket, the combination with a central frame, of the shells or scoops hinged by their inner corners to the frame, and a fluid-pressure mechanism mounted on the frame and connected to the outer edges of the shells for operating them.

8. The combination with the frame, of the shells or scoops hinged thereto by their inner corners, a fluid-pressure cylinder mounted in the frame, a cross-head connected to the piston in said cylinder and guided in said frame, and arms connecting the cross-head to the outer edges of the shells or scoops.

9. The combination with the frame and shells hinged thereto, of arms connected to the shells for operating them, and links hinged to the frame and to the rims of the shells for bracing them during operation.

10. The combination with the frame and

the shells mounted thereon, of the steel blade or anchor extending across the lower end of the frame, and removably secured thereto that it may be replaced when worn out or broken.

11. The combination with the frame and the fluid-pressure cylinder mounted therein, of a blade or anchor extending across the lower end of the frame and provided with a shield for said cylinder.

12. The combination with a dredging-bucket having a slot in its upper end and the chains or cables by which the bucket is suspended, of an equalizing-bar to the ends of which the chains or cables are attached, said bar being pivoted at its middle in said slot and protected throughout its extent by the walls of the slot.

13. The combination with a dredger and its bucket, of a fluid-pressure-operating device located at the bucket, flexible tubes connected to said device, and automatic means on the dredger for taking up and paying out said tubes as the bucket is raised or lowered.

14. In a dredging-bucket, the combination with a frame and anchoring-blade, substantially as described, of the shells or scoops

hinged to the frame and having their outer surface concentric with the axis of the hinge whereby any tendency on their part to lift the bucket during the scooping action is overcome.

15. In a dredging-bucket, the combination with a frame and anchoring-blade, substantially as described, of the shells or scoops hinged to the frame and having their outer surface concentric with the axis of the hinge and their inner surfaces eccentric thereto whereby the scoops are thicker near the rim and tend to enter deeper into the material to be scooped up.

16. The combination with the frame and the fluid-pressure cylinder mounted therein, of a shield for the cylinder located beneath it, and means for anchoring the bucket secured to the lower end of the frame.

Signed at New York, in the county of New York and State of New York, this 5th day of April, A. D. 1899.

WILLIAM H. ARNOLD.
